Val. J. Mullery.

By Horace F. Nichols

his Attorney.

UNITED STATES PATENT OFFICE.

VALENTINE J. MULLERY, OF ST. PAUL, MINNESOTA, ASSIGNOR TO MULLERY PAPER
BOX COMPANY, A CORPORATION OF MINNESOTA.

COLLAPSIBLE BOX.

Application filed March 16, 1921. Serial No. 452,669.

To all whom it may concern:

Be it known that I, VALENTINE J. MULLERY, a citizen of the United States, and resident of St. Paul, in the county of Ramsey 5 and State of Minnesota, have invented a new and useful Improvement in Collapsible Boxes, of which the following is a specification.

My invention relates to collapsible boxes 10 and has for its object to provide a box formed of a single piece of material adapted to be collapsed in a compact state for shipping or to be readily opened up and assembled for use.

Another object of the invention is to cut 15 the box out of a sheet of material so as to practically utilize every particle of the material and so avoid waste.

A still further object is to provide seams 20 on the bottom flaps of the box which are adapted to extend across the same in a manner to stiffen the box where the same has been folded.

In carrying out my objects I cut the box 25 out of a single piece of material and score the same so that two sides are formed complete while the two ends are formed in halves. The sides and ends as well as the bottom are adapted to fold over on score 30 lines so as to provide two oppositely facing corresponding portions of the box which have oppositely facing corresponding edges. These may be secured together in any desirable manner. Between the end portions I 35 form flaps which are adapted to overlap the bottom when the box is opened, said flaps being also formed in halves and simultaneously secured together with the ends.

The full objects and advantages of my invention will appear in connection with the 40 detailed description thereof and are particularly pointed out in the claims.

In the drawings, illustrating the application of my invention in one form—

Figure 1 is a perspective view of my improved box.

Figure 2 is a perspective view similar to Fig. 1 with the box turned bottom side upward and the cover removed.

Figure 3 is a section taken on line 3—3 of Figure 2.

Figure 4 is a plan view of the box after the same has been collapsed.

Figure 5 is an end view of the box shown in Figure 4.

Fig. 6 is a developed view of the box blank after the same has been scored and cut.

As best shown in Figure 1, my improved box comprises a body portion 10 which consists of four sides 11, 12, 13 and 14 and a bottom 15 leaving the top of this portion of the box open. A cover 16 is provided which is formed with sides 17 and 118 and is adapted to be placed over the edges of the sides 11, 12, 13, and 14 to form a closure for the body portion 10. The entire box 10 and cover 16 thereon are held in place by means of a cord or other suitable device 18 which passes partly through the sides 11 and 14 of the device and is adapted to be tied in a knot 60 as clearly indicated in Figure 1. The side members 17 of the top 16 are provided with creases at 19 and 20 by means of which the sides of the top 16 may be collapsed to lie 65 perfectly flat.

The exact construction of the body portion 10 of my invention is most clearly shown in Figure 6. This entire member is cut from a single piece of stock as indicated in Figure 6 with substantially no waste of material. 70 The stock is scored in parallel lines 21, 22, 23 running across the sheet and at longitudinal lines 24, 25, 26 and 27 running at right angles to the first named lines. By means of these score marks the box is divided into its 75 various elements forming the sides 13 and 12 and the bottom 15 each integral and connected together. The sides 14 and 11 are formed in two pieces 28 and 29, which pieces 29 have narrow strips 30 formed along the 80 edges thereof by the score lines 26 and 27. Attached to the pieces 28 and 29 are flaps 31 and 32 which are cut out of material between 85 said portions 28 and 29 and are severed from each other and from the bottom 15 on lines 33, 34, and 35. These flaps may be made 90 with rounded off corners 36 as clearly indicated in the drawings.

After the blank for forming my improved box has been cut and scored as shown in Figure 6, the same may be assembled as follows: Score mark 22, as may be noted in Figure 6, divides the bottom 15 into two sections 37 and 38. The box is folded over on line 22 so that the two halves of the same fall 100 along the same plane as is indicated in Fig-

ures 5 and 4. The strips 30 which are attached to the side members 29 and flaps 31 are then coated with glue and are bent over and glued to the edges of the flaps 32 and 5 the side members 28 so that the box has the appearance indicated in Figure 5. The body portion 10 of my improved box is now completed and ready to be shipped.

In erecting the box the following procedure is necessary. Sides 12 and 13 which lie adjacent each other as indicated in Figure 5 are spread apart. Whereupon the side portions 28 and 29 and the bottom portions 37 and 38 readily straighten out to lie 10 in individual planes. After the box has been spread out to occupy a rectangular space the flap members 31 and 32 are folded over the bottom portion 15 as indicated in Figure 2. This completes the operation of 20 preparing the box for use and said box when set on its bottom will stand erect without further support than its own weight while the same is being filled with the merchandise which it is to carry. After 25 the cover 16 has been placed over the opening of the box and the cord is properly secured around the same as indicated in Figure 1, the box is ready to be delivered with the respective merchandise in it.

30 The advantages of my invention are manifest. The box blank is cut out of a sheet of stock with practically no waste of material. The seams for the edges of the box occur adjacent the lines on which said box is folded and therefore serve to stiffen the sides or ends of the box which are otherwise weakened by the scoring necessary in preparing the sides for folding. The box when folded or collapsed is substantially of the 35 same thickness throughout and great numbers of these boxes may be conveniently piled in warehouses or boxed ready for shipment occupying a minimum amount of space. The side members which are folded 40 through their centers are furthermore provided with flaps which are adapted to fold outwardly at right angles to the center folds in said sides thereby stiffening the whole device so that the entire structure is rigid 45 and substantial.

In accordance with the patent statutes I have described the principles of operation of my invention, together with the apparatus which I now consider to represent the 55 best embodiment thereof, but I desire to have it understood that the construction shown is only illustrative and that the invention can be carried out by other means and applied to uses other than those above 60 set forth within the scope of the following claims.

I claim:

1. A box formed from a blank having

a score line extending across the center portion of the same, a pair of parallel score 65 lines positioned one on each side of said center score line and extending completely across said box blank, a pair of transverse score lines extending completely across said box and at right angles to said first score 70 lines, said blank being severed along said transverse score lines between said two second named parallel score lines and being further severed along said first named center score line between said transverse score 75 lines and the edges of the blank.

2. A collapsible box comprising a body portion forming a bottom to the box, sides formed integral with said bottom extending outwardly therefrom in opposite directions, pairs of end sections formed on said side members extending outwardly therefrom at right angles to the direction of extent of said sides from said bottom, and complementary flap sections formed on said 80 end sections and extending outwardly therefrom at right angles to the direction of extent of said end sections from said side sections, said flaps being totally severed from the bottom portion of the box. 90

3. A collapsible box including a pair of side members, a bottom formed integral with said side members adapted to be folded in its center, pairs of end sections formed integral with said side members extending outwardly therefrom beyond said bottom and pairs of flap sections formed integral with said end members extending outwardly therefrom toward one another adjacent said bottom, said flap sections being 95 separated from said bottom and from one another along the line of folding of said bottom.

4. A collapsible box including a pair of side members, a bottom formed integral 105 with said side members adapted to be folded in its center, pairs of end sections formed integral with said side members and extending outwardly beyond said bottom, and end flaps formed integral with said end sections 110 positioned between opposite pairs of end sections, said flaps being severed from the bottom and from one another.

5. A box formed from a blank having a bottom member at the center thereof, side 115 members connected to said bottom sections, end sections connected to said side members, flaps connected to said end sections and separated from one another and from the bottom of said box, said blank being adapted 120 to be folded along a line separating said flaps and dividing said bottom in half and means for securing said overlapping end sections and flaps together.

In testimony whereof I affix my signature.

VAL. J. MULLERY.
